UNITED STATES PATENT OFFICE.

IRA EUGENE BARR, OF VICTORIA, BRITISH COLUMBIA, CANADA.

HOLLOW-BUILDING-BLOCK WALL CONSTRUCTION.

Application filed June 17, 1924. Serial No. 720,588.

The invention relates to improvements in hollow building block wall construction, the blocks being made from a suitable plastic material by moulding singly or by the continuous die and wire cut-off process and afterwards hardened, being preferably a burnt clay product.

The object of my invention is to improve the construction of hollow building blocks into a design most suitable to all forms of horizontal wall construction, and at the same time conform with all building codes as they are applied in the different cities.

A further object of my invention is to provide improved hollow building blocks that are novel, light—yet strong, simple, and inexpensive, easy to manufacture, ship, and handle and easy and simple for the contractor to figure and lay into a well locked, well aligned, moisture-proof, fire-proof and a load-bearing wall of any required thickness, with or without a brick veneer; thus an improved wall construction system is obtained.

A main block of novel construction, with the use of parts thereof moulded separately and used in connection when required to form walls and structures, thus giving a wall of systematic construction.

The main block thus provided is rectangular in form, having an extended vertical longitudinal wall therefrom, of novel construction itself, which with the block and wall construction has many combined features several as set forth:

1st. The said extended wall being longitudinal and higher than the mortar, the continuous horizontal mortar bed is broken, and having a longitudinal hole therethrough, forming a dead air space directly between the mortar beds thus formed, prevents dampness from passing through the structure.

2nd. Being reasonably thick and solidly moulded on continuous material extending from the inner to the outer surface of the block, dislocation is prevented when laid into a wall; thus a strong transverse and compressive strength is obtained with vertical walls and webs held in alignment with those above and below.

3rd. Being reasonably high and thick a fair sized hand hold is obtained for handling, thus increasing the speed in handling and laying into a wall with the result of a saving in both time and labor, which means money.

4th. The longitudinal holes therethrough

form a very strong lock at the ends of each block with the adjacent blocks when mortar is applied and thus holds and confines the mortar so tight that dampness can not pass through this vertical mortar joint.

5th. The said longitudinal holes therethrough with a slight inward curvature on each side of the said wall, form a good thumb and finger hold for handling and reduce the material to a minimum for results obtained.

6th. The said extended wall is scored on each side at its base which does not interfere with its strength but allows the wall to be broken off to suit the requirements for joists, topping of a wall or story and for corners, etc., and still leave the block with continuous material to hold it together as before.

7th. In working connection with the said extended wall a corresponding opening is formed for receiving the said wall by raising the lower plane of an intermediate member above the lower planes of the outer members to a greater height than that of said wall, thus leaving when laid into a wall a dead air space above and on the sides of the said wall, over the inner edges of the horizontal mortar beds and over the non-continuous vertical mortar joints at the ends of the said extended wall, thus forming an additional protection against the passage of dampness through the structure.

The combined features as set forth are interdependent one to another to obtain the required results in actual practice, similarly the block to wall construction in like manner.

Having other objects and advantages in view, I form my blocks and walls as shown in the accompanying drawings which form a part of this application, it being understood that minor changes can be resorted to without departing from the spirit of this invention.

Fig. 1 is an isometric view of the main block as it is used in a wall and is made preferably the height of two brick inclusive of the mortar joint in between them. The blocks can be made to any reasonable height by adding horizontal webs and any reasonable width by adding vertical webs to keep them within the limits of the building codes.

Fig. 2 is an isometric view of an outer portion of the main block as shown in Fig. 1 as used with the main block when required for

obtaining a wall of more than one block thickness.

Fig. 3 is an isometric view of the portion of the main block as shown in Fig. 1 used with the main block when required for bonding walls together, bonding in a brick veneer, and is used for bonding in at openings and other purposes as occasion demands.

10 Fig. 4 is an isometric view of a wall of one block in thickness. Half length blocks are used to even up vertical openings, thus allowing all blocks to break vertical mortar joints as the wall goes up, with all vertical walls and webs in alignment.

15 Fig. 5 is an isometric view of a corner showing a portion of the extended wall of the main block broken off to allow the incoming course above to lap crosswise to and including the portion thus broken off and the next incoming course above alternating positions. A common vertical block the height of the main block is used in connection with bonding the corners.

20 Fig. 6 shows plans of alternate courses of corner blocks as shown in Fig. 5 for clearness.

25 Fig. 7 is a vertical end view of a wall with a brick veneer showing the bonding block used in connection with headers.

30 Fig. 8 is a vertical end view of a wall with brick veneer showing the small block as shown in Fig. 2 used in connection with the main block as shown in Fig. 1 as required for headers. Double and single headers can be had at any point.

35 Fig. 9 is a vertical end view showing the method of varying the thickness of a wall as required. The small block as shown in Fig. 2 is used in connection with the main block as shown in Fig. 1. The small block being laid parallel to the main block at a distance equal to the width of the longitudinal opening in the base of the main block; the courses above alternating positions or changing combinations as required with the extended wall in direct alignment, vertically, with the spaces between the blocks.

40 Fig. 10 is a vertical end view of a wall showing the bonding block as shown in Fig. 3 used to bond walls together, to bond with itself to reduce the wall in thickness and how it may be used in a wall of one block thickness.

45 In several figures I have indicated the main block as shown in Fig. 1 by "A", the outer portion of the main block as shown in Fig. 2 by "B", and the portion of the main block as shown in Fig. 3 by "C". The half length portion of the main block as shown in Fig. 4 by "D", the vertical corner tie block as shown in Fig. 5 by "F", the portion of the main block with the extended wall broken off a distance for bonding corners by "G", and also two of the main blocks

which are different from the drawings but the same in principle, those in Fig. 4 being indicated by "E" and those in Fig. 10 by "H". Similar characters and numerals of reference denote corresponding parts throughout the several views.

50 Fig. 1 is an isometric view of the main block as used in a wall and consists of hollow rectangular members "4" and "5" of equal length and in horizontal alignment on their upper planes "7". The outer members "4" are of equal height while the intermediate member "5" is of less height by having its lower plane "3" raised above the alignment of the lower planes "10" of the outer members "4", thus forming a longitudinal opening "2" below the intermediate member "5" for receiving a vertical wall "1" extending upwardly from the plane "7" of the intermediate member "5". The longitudinal opening "2" is of a greater height and width than the extended wall "1", thereby forming, when laid into a wall, a dead air space above and on the sides of the said wall "1", preventing dampness from passing through the structure. The said extended wall being directly over an intermediate member "5", thus breaking the continuous horizontal mortar bed at a point where mortar is not required to carry weight, thus a saving in mortar equalling more than the cost of the material in the said wall "1".

55 With the dead air space above and on the side of the said wall "1" and the longitudinal hole "6" extending therethrough, being a dead air space and directly between the two horizontal mortar beds thus formed, dampness is completely checked. The extended wall "1" is strongly moulded on continuous material extending from the outer to the inner surface of the walls of the block, preventing dislocation of the blocks and holds them in alignment with those above and below. The longitudinal hole "6" forms a very strong lock at the end of each block with the adjacent blocks when mortar is applied. The blocks have grooves "9" on their upper planes "7" and corresponding on their lower planes "10" for receiving the mortar, thus forming a very strong interlock.

60 The blocks also have grooves "9" on the outside for stucco or cement coating, and on the inside for plaster direct, but may be left plain when desired.

65 The longitudinal hole or holes "6" not only reduces material and provides insulation but allows the whole block to be hardened uniformly. The inward curvature "8" on each side of the extended wall "1" is still a further reduction of material and gives a good thumb and finger hold for handling, thus increasing the speed in handling and laying into a wall. The outer walls "11" and the inner webs "12" are always in ver-

tical alignment with the walls and webs above and below with the blocks directly superposed.

When necessary the blocks may be increased in width by widening the blocks in proportion or by extending one or both sides to secure the required width, thus the blocks of the larger size would be interchangeable with the smaller size with all vertical walls and webs in alignment with those above and below.

A score is made on each side of the extended wall "1" at its base at "13", in order that it can be broken off at that point to suit the requirements for joists, topping off a wall or story, and at corners, etc. and still leave the block with continuous material to hold it together as before.

The weight of a block depends upon its length and height, and when shortened, the extended longitudinal wall "1" is reduced to a height that will still allow a reasonable hand hold, thus a light block would only require one longitudinal hole "6" throughout, while the heavier blocks would require two.

The continuous material "7" aids in manufacturing and has its many advantages.

Fig. 2 is an outer portion of the main block as shown in Fig. 1 and corresponds to said outer portion "4" of the main block in every respect. This block is used parallel to the main block or blocks at a distance corresponding to the distance across the longitudinal opening at the base of the main block, thus courses are formed for the required thickness of the wall, with any or all of the adjacent courses above alternating positions or changing combinations, as the case might be, to obtain a wall of the required thickness. This system avoids making the larger size blocks, which are quite unhandy to manufacture, handle and lay into a wall, due to their weight.

Fig. 3 is a novel hollow building block within itself but is a portion of the main block as shown in Fig. 1, it being formed by raising the lower plane "10" of one of the outer members "4" of the main block to a height corresponding to the height of a brick plus the mortar, thus allowing the bonding in a brick veneer, bonding walls together, bonding in at openings, bonding with itself and many other purposes.

Fig. 4 is an isometric view of a wall of one block in thickness in which the blocks are superposed and break the vertical mortar joints "16". The half length block "D" is used to even up the wall at openings. The larger blocks "E", having horizontal webs "17" added to suit its height, are interchangeable with the smaller blocks "A". The extended wall breaks the continuous horizontal mortar bed "15", thus forming two distinct mortar beds above the members

"4" of each block, being a preventative against dampness. The longitudinal hole "6" extending through the said wall "1" is a dead air space within the said wall "1" and directly between the horizontal mortar beds "15" is a further preventative against dampness, likewise with the dead air space in the intermediate member "5" below, and the dead air space "14" above and on the sides of the said wall "1" which extends over the inner edges of the horizontal mortar beds "15", thus completely checking dampness horizontally.

The longitudinal hole "6" forms a very strong lock at the end of each block with the adjacent blocks when mortar is applied at "16", thus confining the mortar and preventing dampness from passing this vertical mortar joint and lock. The tight confining of the mortar at this lock joint "16" with the air space "5" within the intermediate member below and with the longitudinal holes being a dead air space on each side of this particular lock joint "16" dampness is completely checked vertically, as well as horizontally.

Fig. 5 is an isometric view of a corner, showing the main block "G" with the extended wall "1" broken off at "18", thus allowing the next incoming course above, with a like block extending crosswise, to and including the portion "19" thus broken off with the next course above alternating positions. A common vertical block "F" is laid at the end of block "G" on each of the incoming courses and bonds the corners with the course above, alternating positions at the corner the same as block "G". The vertical webs of block "F" are in alignment with those of block "G" above and below and likewise with itself, thus a very strong corner is formed and is well insulated owing to the position of the different blocks.

Fig. 6 is a plane of alternative courses of the block "G" and "F" as shown in Fig. 5 for clearness and has the same references.

Fig. 7 is a vertical end view of a brick veneer with the bonding block "C" as shown in Fig. 3 being used with the main block "A" as shown in Fig. 1 to bond the headers "20" at any point required.

Fig. 8 is a vertical end view of a brick veneer with the smaller block "B" as shown in Fig. 2 being used in connection with the main block "A" as shown in Fig. 1 for brick headers "22". Double or single headers can be had at any point regardless of the thickness of the wall. A portion of the extended wall "1" is broken off the main block "A" at "21" for joists. Courses of the different blocks are spaced apart "24" with the courses above alternating positions, thus a wall of more than a block thickness can be had with a brick veneer.

Fig. 9 is a vertical end view of a wall

varying in thickness being reduced as the wall goes up at "23" to suit all the requirements necessary in horizontal wall construction. To obtain a wall of different thickness 5 the main block "A" as shown in Fig. 2 is used and the smaller portion block "B" as shown in Fig. 2 is used in connection. The main blocks "A" are laid end to end, thus forming a course and likewise with the 10 smaller block "B". To obtain the thickness equalling the main block "A" and the portion block "B" plus the distance they are spaced "24" a course of each are laid parallel a distance corresponding to the width of 15 the longitudinal opening at the base of the main block "A" with the adjacent courses above alternating positions, with the extended vertical wall "1" between the blocks and in direct vertical alignment with the 20 course spaces "24". A wall of two block thickness is formed with two main block courses "a" laid parallel at a distance corresponding to the width of the longitudinal opening of the main block "a" with the adjacent courses above comprising two courses 25 of the portion block "b" with a course of the main block "a" intervening with the next adjacent courses above reverting back to the two courses of the main block "A" 30 with all walls and webs in alignment with those above and below and with the longitudinal wall "1" in alignment with the spaces "24" between the blocks. A wall of a greater thickness is had by using the required courses of main block "a" and the portion block "B" and spaced as described 35 with a part or all of the adjacent courses above alternating positions or changing combinations as required.

40 Fig. 10 is a vertical end view of a wall with the bonding block "C" as shown in Fig. 3, being used to bond walls together at "25" in the same manner as a brick header. A hollow building block the height of a

brick can be used in like manner. The block 45 is quite useful and will bond with itself as shown at "26", thus the wall can be reduced in thickness to a single block. The lower courses of the wall is composed of a very high block "H" with horizontal webs 50 added at "27" to suit its height. This block has advantages in strength owing to its heaviness. Insulation pads can be used in connection with the longitudinal hole "6". The said hole "6" allows the pads to enter 55 a short distance therein, and likewise with the adjacent blocks. The main block as shown in this figure has only one longitudinal hole "6" therethrough, due to the shortness of the hand hold. Short light blocks 60 are preferable, but all manufacturers do not have short cut-off arrangements, hence the extended longitudinal wall, I will vary in height and thickness in order to secure a 65 hand hold most suitable to handle the weight, consequently the longitudinal holes will vary in number.

What I claim and desire to secure by Letters Patent, is:

70 A hollow interlocking tile, comprising a body portion formed of hollow side sections and an intermediate section open at the bottom and provided with a transverse web forming with the top of the body portion a hollow section of less height than the side 75 sections and wholly closed against the same, and a rib rising from the top of the body portion in line with and of less width than the intermediate section, said rib being formed with a longitudinal opening with its 80 bottom wall in line with and forming part of the upper surface of the body portion, whereby to permit separation of the rib from the body portion without opening the intermediate section. 85

Signed and dated at Victoria, B. C. this 11th day of June 1924 A. D.

IRA EUGENE BARR.
